OPHTHALMIC MOUNTING

Edward M. Splaine, Southbridge, Mass., assignor
to American Optical Company, Southbridge,
Mass., a voluntary association of Massachu-
setts.

Application January 10, 1936, Serial No. 58,478
In Canada October 18, 1935

12 Claims. (Cl. 88—47)

This invention relates to improvements in ophthalmic mountings and has particular reference to improved lens holding means and method of making the same.

5 This application is a continuation in part of my copending application Serial No. 744,917 filed September 21, 1934.

One of the principal objects of the invention is to provide an improved lens holding means that 10 will resiliently ease off the rigidity in the connection of the holding means to the lens, that will insure the said holding means returning to its initial aligned position after such easing off, that will provide means for controlling the tension of 15 the resilient means during use, that will maintain the connection of the holding means to the lens firm and substantially rigid to prevent looseness and play during the use of the mounting and yet be of such a nature as to relieve shocks and strain in the lenses when the glasses are dropped or 20 roughly handled and that will eliminate the exactness and accurateness in the fitting of the parts to be connected usually required in mountings of this character in the past.

25 Another object of the invention is to provide resilient means of the above character having a plurality of overlying sections, each of which forms a resilient backing support for the adjacent section, and each of which may be of equal or varied resiliency, as desired.

Another object is to provide novel means and method of forming the resilient means and of attaching said resilient means to the lens holding means whereby the opposite ends of the resilient 30 means will exert forces on the lens holding means acting substantially in equilibrium about the connection of the lens holding means to the lens.

Another object is to provide lens holding means of the above character so constructed that the 35 tension of the resilient means may be varied as desired.

Another object is to provide lens holding means of the above character having a relatively rigid portion and a relatively resilient lens edge engaging portion, said resilient portion being formed of a plurality of overlying sections of the same resiliency or of varied resiliencies, as desired, and being adapted to urge the relatively rigid portion into engagement with the periphery of the lens 40 to maintain the parts in desired aligned relation with said lens, said rigid portion being adapted to provide means for varying the tension of the resilient means and also adapted to control the position of alignment of the lens holding means 45 with the lens when the parts are connected.

Another object is to provide lens holding means having a part definitely shaped to produce a pleasing stream-line effect horizontally of the lens in combination with edge engaging means for resiliently maintaining the said part in desired aligned 5 relation with the lens in instances wherein the edge of the lens at the location of attachment of the holding means lies at an angle other than normal relative to the horizontal meridian of the lens and which will resiliently permit movement 10 of the holding means both upwardly and downwardly with respect to its point of attachment to the lens to absorb shocks and strain in either direction.

Another object is to provide a relatively narrow 15 attachment for the resilient means to the lens holding means in the direction of the edge of the lens whereby the conventional rigid backing shoes usual in prior art structures of this nature are eliminated and the normal pivotal action of the 20 lens holding means on the lens will be greatly increased.

Another object is to provide the backing for the resilient means on the lens holding means with relatively straight transversely extending upper 25 and lower edge portions whereby the said edge portions will have a line contact with said resilient means when they are flexed.

Another object is to provide the resilient means with relatively straight transversely extending 30 end portions whereby the said resilient means will have line contact with each other and with the lens at their respective ends.

Another object is to provide novel means functioning separately of the lens face engaging portions of the lens holding means for attaching the resilient means to said lens holding means and for preventing twisting of said resilient means sidewise relative to said lens holding means during use.

Another object is to provide the resilient means nearest the lens with cylindrical shaped end contacts with the edge of the lens whereby a substantial line contact transversely of said edge will exist at different positions of flexing of the resilient means.

Another object is to provide novel means and method of making lens holding means of the above character.

Other objects and advantages of the invention 50 will become apparent from the following description taken in connection with the accompanying drawing, and it will be understood that many changes may be made in the arrangement of parts, details of construction and methods 55

shown and described without departing from the spirit of the invention as set forth in the accompanying claims. I, therefore, do not wish to be limited to the exact arrangement of parts, details 5 of construction and methods shown and described as the preferred forms only have been shown by way of illustration.

Referring to the drawing:

Fig. I is a fragmentary front elevation of an 10 ophthalmic mounting embodying the invention and showing high position straps or lens holding means;

Fig. II is a fragmentary enlarged view of the 15 high position strap shown partially in section;

Fig. III is a perspective view of a modified form 20 of the invention;

Fig. IV is a sectional view of the lens strap 25 shown in Fig. III;

Fig. V is a fragmentary face view of the 30 connecting means for uniting the spring sections with the main body portion of the lens straps shown in the various figures of the drawing;

Fig. VI is a sectional view taken on line 35 VI—VI of Fig. V;

Fig. VII is a view similar to Fig. II showing 40 another modified form of high position strap or lens holding means;

Fig. VIII is a view similar to Fig. VII showing 45 another modified form of the invention; and

Fig. IX is an enlarged sectional view taken on line 50 IX—IX of Fig. VIII.

Much difficulty has been encountered in the past in fitting and securing the lens straps or holding means of rimless type ophthalmic 55 mountings to the lenses and in preventing the said straps or holding means becoming loose and wobbly during use, particularly when the lens straps or holding means were removed from the geometrical center line to a high position 40 on the lens as shown in the present invention. One of the difficulties has been that of maintaining the parts in proper aligned and fitted relation with each other and of fitting the parts so that when the attaching means is placed in 45 the aligned openings formed in the straps and lens no strain will be imparted to the lens with a danger of causing it to become broken during use. This was due primarily to the unsymmetrical nature of the contour of the lens at 50 the high position. Means have been provided, in the past, for resiliently taking up the looseness and play in lens holding means of this character but such means, in most instances, provided resiliency only in one direction of movement of 55 the lens holding means on the lens and due to the restricted size of such devices were not sufficiently durable to produce the most desirable structure, that is, the resiliency of the resilient means would soon play out and permit the parts 60 to loosen and move out of aligned relation with each other during use or when the lens holding means were properly fitted on the lens they were more or less restricted in their movement, 65 that is, the lens holding means were not of a free acting nature.

It, therefore, is one of the primary objects of this invention to provide resilient means for devices of this character which will take up the 70 looseness or play in the connecting means to the lens, which will more or less permanently maintain a shock absorbing cushion connection with the lens and resiliently hold the parts in desired aligned relation with each other and 75 which will provide free acting resilient shock and

strain absorbing means whose forces at its points of contact with the edge of the lens will act substantially in equilibrium on opposite sides of the means for connecting the lens holding means to the lens.

Another object of the invention is to provide 5 means and method of reinforcing the resilient means to produce a more permanent and durable construction and of so forming and connecting the resilient means that they will not move 10 out of aligned relation with each other during use.

A further object is to provide a freer and wider 15 range of flexing than has been usual in the past in devices of this character.

Referring more particularly to the drawing 20 wherein like characters of reference designate like parts throughout the several views, the improved holding means or strap 1 embodying the invention, as shown by one portion of Fig. I and in Fig. II, comprises a portion 2, which when viewed from the front is relatively straight, and has a temple connection 3 adjacent one end thereof and a bifurcated portion 4 adjacent its opposite end. The bifurcations of the portion 4 25 are adapted to engage with the front and rear surfaces of the lens 5 and are provided with openings aligned with an opening in the lens through which attaching means 7, such as a screw or other suitable means known to the art, 30 is extended.

The lens holding means 1 is provided at the 35 base of the bifurcation with an edge engaging member 6 which is normally rigid but of an adjustable nature. This lens edge engaging member, as shown in Fig. II, extends outwardly of the lens holding means at one side, preferably the lower side, and is so formed that it extends transversely to the longitudinal axis of the relatively straight portion 2 and lies at an angle 40 thereto other than normal so as to fit the angle of the upper edge of the lens at the point of attachment of the holding means.

The portion 2, at the base of the bifurcated member, is recessed, as shown at 8, to receive 45 the sections 11 and 12, of the resilient lens edge engaging means 9. The resilient means 9, as shown in Figures I and II, comprises three sections 11, 12, and 13 and each section is provided with an opening through which securing means 10 on the base of the bifurcation extends. The securing means is headed over to secure the said sections in superimposed relation with each other and to attach them to the base. The detail of construction of the securing means 10 will be set forth in detail hereinafter. These various sections are of different lengths and may be of varied resiliency with the longest section 13 more resiliant than section 12 and the said section 12 more resiliant than the shorter section 11. Although I have shown and described only three sections of varying lengths and varying degrees of resiliency, it is to be understood that the number of said sections may be varied, that is, increased or decreased, and that the said sections may be 55 made of material having substantially the same degree of resiliency if desired. The function of the resilient means 9 is similar to that of a leaf spring wherein a resilient section forms a backing support for another adjacent section. Attention is directed to the fact that the sections 11 and 12, attached in the recess 8 by the connecting means 10, are held by the side walls of said recess against movement sidewise, and are thereby prevented from twisting out of aligned relation with 60

each other during use. The section 13 may also be placed in the recess 8 if desired. The inner walls of the bifurcated portion 4 also in some instances aid in preventing movement of the sections sidewise during use. The connecting means 7 which holds the lens holding means 1 in secured relation with the lens 5 is fitted during the assembling of the parts so as to have a predetermined amount of looseness and play to permit the said holding means to move about the said connecting means as a center during use. This looseness and play, however, is such as to prevent movement of the lens holding means in a plane normal to the plane of the lens, that is, the movement of the holding means about the pivot 7 in this instance is entirely in the direction of the plane of the lens. It is apparent that by adjustment of the member 6 outwardly or inwardly relative to the peripheral edge of the lens, the tension of the resilient means 9 may be varied and the position of the lens holding means relative to the lens may be varied, that is, the longitudinal axis of the portion 2 may be varied with respect to the horizontal meridian of the lens so that the said portion may be placed in parallel or other desired relation with the horizontal meridian of the lens to produce a pleasing streamline effect transversely of said lens. The resilient means 9 provides means for taking up the looseness and play in the connection of the lens holding means to the lens and also provides free acting and durable means for absorbing shocks and strain on the lens during the use of the mounting. This arrangement obviates the necessity of having to closely associate and fit the parts with each other prior to placing the connecting means 7 in the aligned openings, and thereby greatly decreases the difficulties usually encountered in the past, in fitting and assembling holding means of this nature with the lenses.

The upper edge 14 of the base of the bifurcation and the free ends of the resilient sections 11, 12 and 13 are preferably formed relatively straight transversely thereof so as to provide substantially line contact with each other and with the edge of the lens when the lens holding means is moved about the lens connecting means 7. This arrangement is of particular importance when the lens holding means is attached to the lens adjacent the upper edge thereof because at this location due to the curvature of the lens, the pivotal axis of the lens connecting means is not exactly perpendicular to the edge of the lens and the plane of pivotal movement of the lens holding means on the lens and the springs, is inclined slightly to the portion of the edge of the lens against which the springs rest. This slight inclination, when the lens holding means is moved about its pivotal connection 7 to the lens has a tendency to cause the superimposed resilient sections to work about their connection to the lens holding means. If the said resilient sections are provided with line contact with each other at their ends and the edge of the bifurcated member, as set forth above, the tendency of the said resilient sections to twist about the connection to the lens holding means and of becoming loosened at said connection would be eliminated.

In Figs. V and VI there is shown an enlarged fragmentary view of the connecting or securing means 10 which extends through the aligned openings in the superimposed resilient sections 11, 12, and 13. The connecting means 10 is in the form of a rectangular pin having a reduced portion 15 adjacent one end thereof secured by solder

or other suitable means to an opening in the body portion 16 of the lens strap, and having projections 17 adjacent its opposite end which during the assembling of the superimposed resilient sections are adapted to be pressed to lie within 5 beveled transverse edges 18 formed in the resilient section 13. During the pressing operation the pin member 10 is compressed, forcing the body portion of the pin into rigid engagement with the side walls of the openings in the superimposed 10 sections 11, 12 and 13, rigidly securing them to the body portion 16 of the lens strap and eliminating all looseness and play in the connection.

The purpose of providing a rectangular shaped pin, the greater width of which extends in the direction of the longitudinal axis of the superimposed sections, is to provide means whereby the width of the portions 19 on the opposite sides of the connecting pin 10 will not be so reduced as to cause them to be weakened to a degree wherein they will not provide a positive and permanent connection and permit the various resilient sections to function properly. That is, the rectangular shape of the pin 10 permits forming these sections to a greater width than has been usual 25 in the past. This also provides a longer bearing surface and thereby prevents displacement of the alignment. The portions pressed into engagement with the beveled end walls 18 provide means for anchoring the resilient means in the 30 direction of flexing and thereby provide a positive and durable attachment.

This method of attaching the resilient means to the base of the lens holding means enables the spaced lens face engaging portions to be adjusted to any desired spaced relation with each other independently of the resilient means. This enables the said holding means to be fitted to lenses of varying thicknesses without danger of having the resilient sections move out of alignment with each other as would be the case if a round pin were used and the inner walls of the spaced face engaging portions were depended upon to hold the resilient sections in alignment. It is quite obvious that with the latter structure, 45 if the space between the lens face engaging portions were increased, as happens when the lens holding means is fitted to a thick lens, the inner walls of said face engaging portions would move away from the side edges of the resilient means 50 with a result that the said resilient means would twist out of alignment during use. The structure shown in Figures V and VI completely eliminates this difficulty.

Referring more particularly to Figures III and 55 IV, there is shown a modified form of the invention wherein a high position strap, such as that shown in Fig. II, is so constructed as to flex downwardly as well as upwardly in the plane of the lens during use. This is accomplished by providing the lens holding means with an upwardly extending support 20 to which the resilient edge engaging means 21 is attached by a headed rectangular pin member 22. This pin is similar to the pin 10 referred to above. Attention is directed to the fact that the point of attachment of the resilient means 34 is in this instance on a line 23 which is substantially normal to a line tangent with the edge of the lens at the location of the holding means on the lens and which extends substantially through the axis of the pin 22 and point of attachment of the connecting means 24 to the lens. This provides the resilient means 21 with substantially equal edge bearing surface on the opposite sides of the point of at- 75

tachment 24 so that when the lens holding means is moved about said point of attachment as a center the resilient means 21 will function substantially equally on both sides of said point.

5 The lens holding means in this instance is provided with a temple supporting portion or arm 25 similar to the previously described portion 16 and which lies substantially parallel with the horizontal meridian of the lens to produce a 10 pleasing streamline effect across the lens. The resilient means in this instance comprises three superimposed sections 26, 27 and 28 of varying lengths having relatively straight transverse end portions 29 providing substantial line contact 15 with each other substantially throughout the full width thereof when flexed. The upwardly extending support 20 also has a substantially straight transverse end 30 providing line contact substantially throughout the width of the 20 adjacent resilient section when the resilient means is flexed towards said support. As previously set forth, this line contact provides wide bearing surface with the rear of the respective resilient sections and prevents their twisting side- 25 wise on the pin member 22 and moving out of aligned stacked relation with each other during use. It will be noted that the pin 22 is offset to one side of the longitudinal axis 31 of the temple support 25 and the center of the connecting means 30 30 24 is offset to the other side of the longitudinal axis 31. The support 20 has an attaching face 32 lying at an angle to the longitudinal axis 31 and substantially tangent to but removed from the edge of the lens. The feature of this construction resides in the fact that the resilient means 21 contacts the edge of the lens at two spaced points, one on each side of the pin 22 and the lens connecting means 24 and is adapted to exert forces on the supporting arm 25 acting 35 substantially in equilibrium about the connecting means 24 when the supporting arm is in its normal horizontal position. The face 32 is cut away at 33 to provide clearance whereby the lower resilient portions will be free to flex rearwardly 40 throughout the major portion of their lengths during use.

It will be noted that the distances between the ends 29 of the various resilient sections and from the edge 30 to the end 29 of the section 26 50 are substantially the same. This is to provide staggered line contact supporting ends or edges at equally spaced intervals intermediate the ends of the resilient section 28 which during the flexing of said section will be successively brought 55 into action to stabilize the flexing of said section throughout its length. The sections 26 and 27 resiliently ease off the flexing of the section 28 and increase its tendency to return to its initial set after such easing off. This function takes 60 place in either direction of flexing about the pivot 24.

In Fig. VII there is shown another modified form of high position strap similar to that shown in Fig. III, only in this instance instead of extending all of the superimposed spring sections both upwardly and downwardly similar amounts on opposite sides of the attaching means 34, the sections 35 and 36 extend upwardly only of the point of attachment 34. In this instance the 65 normally relatively short resilient backing member or section 37 is provided with an elongated downwardly extending spring portion 38 forming the lower lens edge engaging means. The spring portion 38 is preferably of a tension substantially equal to the combined tension of the sec- 75

tions 35 and 36 so as to substantially equalize the lens edge engaging pressure on the opposite sides of the point of attachment 39 of the lens strap to the lens.

Attention is directed to the fact that in this instance the attaching means 34 for securing the various sections 35, 36 and 37 to the lens holding means is not positioned on a line substantially normal to a line tangent with the edge of the lens at the location of the holding means on the lens, and which extends substantially through the axis of the point of attachment of the connecting means 39 to the lens, but the related positions, resiliency and dimensions of the superimposed sections 35, 36 and 37 are such as to provide substantially equal resiliency on the opposite sides of the point of attachment 39. The alignment of the holding means on the lens may be varied by the proper adjustment of the spring section 38. If desired, however, the point of attachment 34 could be positioned on a line normal to a line tangent with the edge of the lens and extending through the point of attachment 39 if desired. This could be accomplished by increasing the lowering of the point of attachment 39 relative to the longitudinal axis of the temple support 40 the proper amount.

The spring sections 35 and 36 may be of equal resiliency or may be varied in resiliency, as desired, that is, the section 36 may be made more rigid than the section 35 in a manner similar to that shown and described in connection with the above figures of the drawing or the sections may be of material having the same resiliency formed to different lengths to render them different in resilient reaction. This is due to different lever actions which cause the spring sections to react differently, the shorter sections being more rigid in their action than the longer sections, etc.

Attention is directed to the fact that there is a clearance provided in the rear of the lower resilient means as indicated at 41, to provide means whereby the lower portion may be free to flex towards or away from the edge of the lens.

It will be noted that the ends 42 of the spring section 35 are flattened or shaped to have substantially intimate contact with the edge of the lens throughout the length of said end portions substantially as shown. This is for the purpose of distributing the pressure of the ends of the spring on the lens throughout an increased area rather than have it concentrated on single spots when the lens holding means is moved on its pivot connection with the lens. This produces a surface contact between the edge of the lens and ends of the spring and greatly relieves the strain which might be introduced at these locations.

In Fig. VIII there is shown another modified form of the invention wherein the ends 43 of the spring 44 are curved to provide substantially cylindrical shaped contact surfaces with the edge of the lens. This provides curved engaging surfaces instead of relatively sharp contacting edges at the ends of the spring but it is to be noted that relatively straight contact of the spring ends with the edge of the lens is still provided. The curved ends may also be formed on the spring sections 45 and 46 if desired. This arrangement as well as the intimate contact of the ends of the spring with the edge of the lens may be used in all of the different structures shown in the drawing.

It will be noted that the face of the support 48 is angled rearwardly, as indicated at 49, on

the opposite sides of the attaching pin 50 to provide more clearance for the flexing of the spring sections rearwardly during use. In this instance the spring section 46 is preferably curved longitudinally and cupped transversely, as indicated in Fig. IX, to increase the initial rigidity thereof prior to attaching the springs to the support 48. The object of this arrangement is to provide means in the rear of the spring sections 44 and 10 45 for preventing their straightening from their desired curved shape during the compressing of the ends of the pin 50, corresponding to the ends 17 in Fig. VI, into engagement with the spring section 44 to secure them to the support 48. If 15 the spring section 46 is not cupped, as stated above, the various spring sections have a tendency to straighten when the ends of the pin 50 are pressed rearwardly to secure the said spring sections to the support. This cupping therefore 20 provides sufficient resistance during the assembling operation to prevent this straightening of the spring and yet provides a resilient backing for the section 45 during use.

In the structure shown in Fig. IV, the face 32 25 of the support 20 is cupped or curved to the approximate curvature of the spring sections 26, 27 and 28 and thereby obviates any tendency of the said sections to straighten when the projections on the pin member 22, corresponding to the projections 17 of Fig. VI, are forced into engagement 30 with the section 28 to attach and hold the various sections in aligned relation with each other on the support 20. The face 32, as well as all of the corresponding attaching faces of the various constructions shown in the drawing, is relatively 35 narrow in the direction of the edge of the lens and is so positioned relative to the edge of the lens that the normal pivotal movement of the lens holding means on the lens is greatly increased 40 and the flexing action of the resilient means is also greatly increased. This arrangement, therefore, greatly increases the shock and strain absorbing characteristics of lens holding means of this nature.

45 It is to be understood that either of the above methods of preventing straightening of the resilient sections during the securing thereof to their supporting means may be used in any of the constructions shown. In the construction shown 50 in Fig. IV, wherein the face 32 is cupped it will be noted that the width of the face in the direction of the edge of the lens is slightly greater than the width of the head of the pin in said direction so that when pressure is applied to said 55 head the resilient means will be compressed intermediate the upper and lower edges of the face 32. The said upper and lower edges being substantially straight transversely of the resilient means will have a tendency to cause the various 60 sections to cup rather than to straighten.

Although the connecting pin shown in Figures V and VI is described as being used in connection with the lens holding means, illustrated in Fig. II, it may be applied to any of the structures disclosed herein.

In all of the above described structures it is apparent that resilient means incorporating a plurality of sections forming resilient backing supports for each other and which may be regulated as to their tension by controlling their lengths and thicknesses have been provided. This type of resilient means overcomes most of the difficulties encountered in prior art lens holding devices of this nature in that it is more 70 durable and maintains a snug and permanently 75

resilient connection with the lens during use. In all instances the conventional rigid backing supports or edge strap portions of the prior art structures have been eliminated and have been replaced by the resilient backing members. This 5 provides a wider range of flexing and more practical and balanced means for absorbing strains and shocks in directions both upwardly and downwardly relative to the plane of the lenses.

From the foregoing description it will be seen 10 that I have provided simple, efficient and economical means and methods of obtaining all of the objects and advantages of the invention.

Having described my invention, I claim:

1. A device of the character described for attachment to a lens at a point removed from the horizontal geometrical center line of the lens, said attachment having a supporting arm the longitudinal axis of which is adapted to be maintained in a substantially horizontal plane when 20 in its position of normal use on the lens and a lens engaging element adapted to be connected to the lens at a point removed to one side of the longitudinal axis of the supporting arm, a portion 25 adjacent one of the ends of the supporting arm adapted to overlie the edge of the lens and formed with a relatively short attaching face for resilient means, said attaching face lying at an angle other than normal relative to the longitudinal axis of said supporting arm, and resilient 30 means secured intermediate the ends thereof to said attaching face for contacting the edge of the lens at two spaced points, one on each side of the point of attachment of said resilient means with said attaching face and on opposite 35 sides of the longitudinal axis of the supporting arm, said point of attachment lying on a line substantially normal to the plane of the attaching face and at an acute angle to the longitudinal 40 axis of said supporting arm and extending through the point of connection of the lens engaging element to the lens, whereby the portions 45 of the resilient means on the opposite sides of the point of attachment will exert forces on said supporting arm acting substantially in equilibrium about the connection to the lens when the supporting arm is in its normal horizontal position.

2. In a device of the character described for attachment to a lens at a point removed from the horizontal geometrical center line of the lens, said attachment having a supporting arm the longitudinal axis of which is adapted to be maintained in a substantially horizontal plane when 50 it is in its position of normal use and a lens engaging element adapted to be pivotally connected to the lens at a point removed to one side of the longitudinal axis of the supporting arm, an offset portion extending from adjacent one end of said 55 arm on one side only and at an angle other than normal relative to the longitudinal axis of the arm and having a face adapted to lie substantially parallel with a line tangent with the edge of the lens at said location when said arm is in a horizontal position of use and resilient means for contacting the edge of said lens at two spaced points and connected to the face of said offset portion at a point removed from the longitudinal axis and at such a location as to exert forces on 60 said supporting arm acting substantially in equilibrium about the pivotal connection to the lens, said face being cut away adjacent the lower portion thereof to lie in a plane further removed 65 from the edge of the lens to provide clearance 70

for the flexing of the lower portion of the resilient means during use.

3. A device of the character described for attachment to a lens at a point removed from the horizontal geometrical center line of the lens, said attachment having a supporting arm the longitudinal axis of which is adapted to be maintained in a substantially horizontal plane when in its position of normal use on the lens and a lens engaging element adapted to be connected to the lens at a point removed to one side of the longitudinal axis of the supporting arm, a portion adjacent one of the ends of the supporting arm lying at an angle other than normal relative to the longitudinal axis of the supporting arm and adapted to overlie the edge of the lens and provide an attaching face for resilient means and a plurality of superimposed resilient members of varying lengths secured to said attaching face 10 by a single attaching member with at least one of said resilient members adapted to contact the edge of the lens at two spaced points on opposite sides of the point of attachment of said resilient means with said attaching face and on the opposite sides of the longitudinal axis of the supporting arm, said point of attachment lying on a line substantially normal to the plane of the attaching face and at an acute angle to the longitudinal axis of said supporting arm and extending 15 through the point of connection of the lens engaging element to the lens, whereby the portions of said resilient means on the opposite sides of said point of attachment will exert forces on said supporting arm acting substantially in equilibrium about the connection to the lens when the supporting arm is in its normal horizontal position.

4. A device of the character described for attachment to a lens comprising a member having an attaching portion for engaging the face of the lens and means for overlying the edge of the lens and extending outwardly of the opposite sides of said member for engaging the face of the lens, one of said means extending outwardly of the opposite sides of said face engaging member comprising a plurality of superimposed resilient members and the other a single resilient member, said single resilient member being formed to a resiliency substantially equivalent to the combined resiliency of the plurality of resilient members.

5. A device of the character described for attachment to a lens at a point removed from the horizontal geometrical center line of the lens, said attachment having a portion adapted to overlie a face of the lens and be pivotally connected to said lens and a portion adapted to overlie the edge of the lens with the major portion thereof lying above a horizontal line extending through the pivotal connection to the lens, said edge portion having an attaching face on the side thereof adapted to lie toward the lens which is relatively short in a direction following the edge of the lens and which is substantially parallel with a line tangent with the edge of the lens at said location when the portion overlying the face of the lens is in its normal position of use, said attaching face lying at an angle other than normal relative to the horizontal center line of the lens when the attachment is on the lens, and resilient means secured to said face and having portions adapted to extend outwardly of the opposite sides of the said horizontal line extending through the pivotal connection to the lens and being adapted 70 to engage the edge of the lens at two spaced

points substantially equidistant from a line extending through the point of attachment of the resilient means to said face and the pivotal connection to the lens to exert forces on said portion overlying the edge of the lens acting substantially in equilibrium about the connection to the lens when the parts are in their normal position of use.

6. A device of the character described for attachment to a lens at a point removed from the horizontal geometrical center line of the lens, said attachment having a supporting arm the longitudinal axis of which is adapted to be maintained in a substantially horizontal plane when in its position of normal use on the lens and a lens engaging element adapted to be pivotally connected to the lens at a point below the longitudinal axis of the supporting arm, a portion adjacent one of the ends of the supporting arm adapted to overlie the edge of the lens and resilient means having a portion attached to said overlying portion above the longitudinal axis of the supporting arm and portions adjacent its ends for contacting the edge of the lens at two spaced points substantially equidistant from the point of attachment of said resilient means with said overlying portion and extending outwardly of the opposite sides of a horizontal line extending through the pivotal connection to the lens when the attachment is on the lens, the portions of the resilient means on the opposite sides of said point of engagement being balanced to exert forces on said supporting arm acting substantially in equilibrium about the pivotal connection to the lens when the supporting arm is in its normal position of use.

7. A device of the character described for attachment to a lens at a point removed from the horizontal geometrical center line of the lens, said attachment having a portion adapted to overlie a face of the lens and be pivotally connected to said lens and a portion adapted to overlie the edge of the lens with the major portion thereof lying above a horizontal line extending through the pivotal connection to the lens, said edge portion having an attaching face on the side thereof adapted to lie towards the lens which is relatively short in a direction which is to follow the edge of the lens and which lies at an angle other than normal relative to the horizontal center line of the lens when the attachment is on said lens, and resilient means secured to said face and having portions adapted to extend outwardly of the opposite sides of said horizontal line extending through the pivotal connection to the lens and being adapted to engage the edge of the lens at two spaced points and being supported so as to exert forces on said portion overlying the edge of the lens in both directions of movement of said portion about the pivotal connection to the lens when the parts are in their normal position of use.

8. A device of the character described for attachment to a lens at a point removed from the horizontal geometrical center line of the lens, said attachment having a portion adapted to overlie a face of the lens and be pivotally connected to said lens and a portion adapted to overlie the edge of the lens with the major portion thereof lying above a horizontal line extending through the pivotal connection to the lens, said edge portion having an attaching face on the side thereof adapted to lie towards the lens which is relatively short and cuped in the direction which is to follow the edge of the lens and which lies at an

angle other than normal relative to the horizontal center line of the lens when the attachment is on said lens and resilient means secured to said cupped face so as to have the portion thereof 5 engaging said face assume the shape thereof and having portions adapted to extend outwardly of the opposite sides of the said horizontal line extending through the pivotal connection to the lens and being adapted to engage the edge of the lens at two spaced points and being supported so 10 as to exert forces on said portion overlying the edge of the lens in both directions of movement of said portion about the pivotal connection to the lens when the parts are in their normal position 15 of use.

9. In an ophthalmic mounting, a lens, a lens holding member having a portion overlying a face of the lens and pivotally connected to said lens at a point removed from the horizontal geometrical 20 center line of the lens and a portion overlying the edge of the lens with the major portion thereof lying above a horizontal line extending through the pivotal connection to the lens, said edge portion having an attaching face on the side thereof 25 adjacent the lens which is relatively short in a direction following the edge of the lens and which lies at an angle other than normal relative to the horizontal center line of the lens when the parts are in their normal position of use, and resilient 30 means secured to said face and having portions extending outwardly of the opposite sides of said horizontal line extending through the pivotal connection to the lens and engaging the edge of the lens at two spaced points and being supported so 35 as to exert forces on said portion overlying the edge of the lens in both directions of movement of said portion about the connection to the lens when the parts are in their normal position of use.

10. In an ophthalmic mounting, a lens, a lens holding member having a portion overlying a face of the lens and pivotally connected to said lens at a point removed from the horizontal geometrical center line of the lens and a portion overlying the edge of the lens with the major portion thereof lying above a horizontal line extending through the pivotal connection to the lens, said edge portion having an attaching face on the side thereof adjacent the lens which is relatively short and cupped in the direction following the edge 45 of the lens and which lies at an angle other than normal relative to the horizontal center line of the lens when the parts are in their normal position of use, and resilient means secured 50 to said cupped face with said resilient means substantially assuming the shape of said face and with portions thereof extending outwardly of the opposite sides of the said horizontal line extending through the pivotal connection to the lens and engaging the edge of the lens at two spaced points and being supported so as to exert forces 55 on said portion overlying the edge of the lens in both directions of movement about the pivotal connection to the lens when the parts are in their normal position of use.

11. A device of the character described for attachment to a lens at a point removed from the

horizontal geometrical center line of the lens, said attachment having a portion adapted to overlie a face of the lens and be pivotally connected to said lens and a portion adapted to overlie the edge of the lens and having a projection on the upper side thereof when the attachment is in its normal position of use, said edge portion and projection having an attaching face on the side thereof adapted to lie towards the lens which is relatively short in a direction which is to follow 10 the edge of the lens and which lies at an angle other than normal relative to the horizontal center line of the lens when the attachment is on said lens and which is formed irregular to provide a portion acting as a support for the attachment of resilient means and a portion forming a clearance for the resilient means on the side of said portion adapted to overlie the edge of the lens opposite the projection for free flexing of the adjacent portion of said resilient means during use and resilient means secured to said support at a point above a horizontal line extending through the pivotal connection to the lens and having portions adapted to extend outwardly of the opposite sides of said horizontal line and being adapted to engage the edge of the lens at two spaced points and being supported so as to exert forces on said portion overlying the edge of the lens in both directions of movement of said portion about the pivotal connection to the lens when the parts are in their normal position of use.

12. In an ophthalmic mounting, a lens, a lens holding member secured to the lens at a point removed from the horizontal geometrical center line of the lens, said lens holding member having a portion overlying a face of the lens and pivotally connected to said lens and a portion overlying the edge of the lens and having a projection on the upper side thereof when the lens holding member is in its normal position of use, said edge portion and projection having an attaching face on the side thereof lying towards the lens which is relatively short in a direction following the edge of the lens and which lies at an angle other than normal relative to the horizontal center line of the lens and which is formed irregular to provide a portion acting as a support for the attachment of resilient means and a portion forming a clearance for the resilient means on the side of said portion overlying the edge of the lens opposite the projection for free flexing of the adjacent portion of said resilient means during use and resilient means secured to said support at a point above a horizontal line extending through the pivotal connection to the lens and having portions extending outwardly of the opposite sides of said horizontal line and engaging the edge of the lens at two spaced points and being supported so as to exert forces on said portion overlying the edge of the lens in both directions of movement of said portion about the pivotal connection to the lens when the parts are in their normal position of use.

EDWARD M. SPLAINE.
